UNITED STATES PATENT OFFICE.

LEONARD D. KROFF, OF STERLING, ILLINOIS, ASSIGNOR TO EVAN L. REED MANUFACTURING COMPANY, OF STERLING, ILLINOIS.

RACK FOR SEED-PACKETS.

1,311,975.

Specification of Letters Patent.

Patented Aug. 5, 1919.

Application filed March 14, 1918. Serial No. 222,351.

To all whom it may concern:

Be it known that I, LEONARD D. KROFF, a citizen of the United States, residing at Sterling, in the county of Whiteside and State of Illinois, have invented certain new and useful Improvements in Racks for Seed-Packets, of which the following is a specification.

My invention has reference to a rack for 10 seed-packets such as displayed in stores. It is simple and durable in construction, and capable of being reduced to a compact space for the purpose of being transported or stored. The latter purpose is important, for 15 the reason that such devices are only in use for a small portion of each year.

In the drawings, Figure 1 is a side view of my device, when in use. Fig. 2 is a front view thereof. Fig. 3 is a vertical section 20 through the body portion of the invention, in partially folded position. Fig. 4 is a perspective view of one of the frames 3.

1 represents a board of any desired form and proportions, provided with series of 25 perforations 2, adapted to receive the ends of frames 3, preferably formed of a continuous piece of wire. Said frames comprise a pair of parallel bars 4 united at one end by a cross bar 5, and diagonal arms 6 30 at the opposite ends of said bars, united in a coiled arm 7. The engaging end of the frame is turned upwardly into a hook 8, formed of the end of one of the wires in the arm 7. The other wire of the coil is cut 35 so as to form a shoulder 9, which has a bearing against the board 1, and limits the extent to which the arm 7 may be projected through such board.

To place one of the frames 3 in position, 40 the outer end thereof is tipped upwardly to permit the insertion of the hook 8 in one of the openings 2. The frame is then turned downwardly until the bar 5 rests against the board 1, holding the bars 4 at approximately a right angle with the face of such board. Said frames are provided in series, 45 as shown in Fig. 2, and when thus arranged are adapted to receive a number of seed-packets 10, of usual shape and size, the 50 lower edges of the packets resting upon the adjacent bars 4 of two adjoining frames. When the holes 2 are provided at proper intervals, the space between two adjacent

arms 7 will be a little greater than the width of the packet, so as to conveniently receive the same. 55

It will be seen that by the construction above described, a plurality of open pockets is formed, in which the packets may be held in bunches, so as to be easily visible for their 60 full lengths, and capable of being readily removed or replaced. The bars 4 form the bottoms of such pockets, the bars 7 the sides thereof, the board 1 the rear, and the arms 65 6 the front.

The engagement of the bar 5 of each of the frames with the face of the board 1 prevents a swinging movement of the frame in one direction or the other. For the purpose of shipment or storage the frames 3 can all 70 be removed and packed together, such frames being capable of being nested one within the other, very compactly.

For the purpose of cheapness of production and durability, the board 1 is preferably formed of a sheet of metal. 75

Any suitable means may be employed for supporting the device, but there is shown in the drawings a folding frame which is especially designed for use therewith. This 80 frame comprises plates 11, attached to the board 1, near the ends thereof, arms 12 pivotally connected with said plates at the upper ends thereof, and cross-legs 13 and 14 pivoted to the lower ends of the members 85 11 and 12, respectively. The spread of the frame, when in open position, is limited by a folding brace 15, having a pivotal connection with the frame at the points of junction of the legs therewith. The pivot 16 of 90 the legs is preferably in the form of a rod, extending from one pair of legs to the other.

When it is desired to fold the frame, the brace 15 is doubled until the parts thereof overlap, which results in the arms 12 coinciding in position with the plates 11, and the legs 13 and 14 overlapping. Such legs can then be turned upwardly and rearwardly, as indicated in Fig. 3, until they come in contact with the board 1. It will 95 be seen that the board and frame thereupon occupy a very limited space. Said folding frame is preferably formed of metal throughout, and it will be obvious that when in open position the structure of said frame 100 is such as to hold the board 1 in a sloping 105

position. This is not essential, but is considered to be more convenient for the purpose of handling the packets of seeds which are supported by the device.

5 The frames 3, which are at the ends of the board 1, may be formed with a vertical bar 17 in place of the usual diagonal bar 6 at the outer side thereof.

10 While my invention has been shown and described herein in its preferred embodiment, and for a specified use, changes can be made in the form and structure thereof, without departing from the spirit of the invention, and the same can be made use 15 of for the support of other articles besides those set forth herein.

What I claim as my invention, and desire to secure, is

20 1. In a device of the class described, in combination with a board, provided with

Copies of this patent may be obtained for five cents each, by addressing the "Commissioner of Patents, Washington, D. C."

suitable perforations, an article supporting member, comprising a pair of parallel bars united by a cross bar at their inner ends, diagonal arms connected with the opposite ends of said bars and united in an arm 25 provided with means for engagement with one of said perforations.

2. In a device of the class described, in combination with a supporting board, provided with suitable perforations, a packet 30 supporting member formed of a continuous piece of wire, and comprising a pair of parallel bars united at one end by a cross bar, diagonal arms at the opposite ends of said bars, united in a coiled arm at a point 35 midway of said parallel bars, and means on the end of said coiled arm for engagement with one of said perforations.

In testimony whereof I affix my signature.

LEONARD D. KROFF.
